US0D1094134S

(12) **United States Design Patent** (10) **Patent No.:** **US D1,094,134 S**
Chen (45) **Date of Patent:** **** Sep. 23, 2025**

(54) **TIRE PRESSURE SENSOR**

(71) Applicant: **Autel Intelligent Technology Corp., Ltd., Shenzhen (CN)**

(72) Inventor: **Huizhi Chen, Shenzhen (CN)**

(73) Assignee: **Autel Intelligent Technology Corp., Ltd., Shenzhen (CN)**

(**) Term: **15 Years**

(21) Appl. No.: **29/878,381**

(22) Filed: **Jun. 21, 2023**

(30) **Foreign Application Priority Data**

Jan. 18, 2023 (CN) 202330027456.7

(51) **LOC (15) Cl.** **10-04**

(52) **U.S. Cl.**
USPC **D10/86**

(58) **Field of Classification Search**

(57) **CLAIM**

The ornamental design for a tire pressure sensor as shown and described.

DESCRIPTION

FIG. 1 is a front perspective view of a tire pressure sensor showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the tire pressure sensor that form no part of the claimed design.

1 Claim, 8 Drawing Sheets
